BRIDGE RETAINING DEVICE

Filed June 16, 1926

2 Sheets-Sheet 2

UNITED STATES PATENT OFFICE.

GEORGE A. YANTIS, OF ELMA, WASHINGTON.

BRIDGE-RETAINING DEVICE.

Application filed June 16, 1926. Serial No. 116,416.

This invention relates broadly to an improved dental appliance, to be used in association with fixed or permanent bridge work, and it has more particular reference 5 to an improved means which may be conveniently designated as a bridge retaining device.

Considerable difficulty is experienced in attempting to properly seat a bridge when 10 the abutment teeth are not parallel with each other, or are otherwise distorted.

What I propose to do, is to so construct the bridge, as to facilitate application, to make a neat job, and to assure permanent 15 maintenance of the bridge, even when the abutment teeth are decidedly out of alignment with each other.

An important object of the invention is to make it possible to properly seat a permanent 20 bridge without distorting the abutment inlays, or the crowns or whatever is used on the abutment teeth in anchoring the bridges in place.

A further object is to make it possible to 25 seat a permanent bridge on abutment teeth that are not parallel with each other without the loss of too much tooth structure on the abutment teeth in trying to make them parallel which is ordinarily essential in 30 order to get a one-piece bridge in place and to provide a neat and perfect fit.

An equally important object is to provide 35 an improved article of manufacture which can be conveniently used by any and all dentists desiring an appliance of this kind, the same being advantageous in that it can be readily associated with the abutment tooth on one side and the adjacent molded 40 dummy tooth.

Other objects and advantages of the invention will become apparent from the following description and drawings.

In the accompanying drawings forming a part of this application and in which like 45 numerals are employed to designate like parts throughout the same:—

Figure 1 is a view in elevation and section showing the improved placement of the bridge work and the special retaining or 50 coupling device therefor.

Fig. 2 is a plan view with portions broken away and shown in section to disclose the manner in which the parts of the coupling cooperate.

Fig. 3 is a perspective view of one of the parts of the coupling.

Fig. 4 is a perspective view of a complementary part of the coupling.

Fig. 5 is a connecting pin.

Fig. 6 is a retaining key for the pin. 60

Fig. 7 is a view showing a slightly modified embodiment of the coupling.

Fig. 8 is a plan view with portions broken away as shown in section of Fig. 7.

Fig. 9 is a perspective view of the parts of 65 the improved coupling.

Fig. 10 is a perspective view of the complementary part.

Attention is first directed to Figs. 1 to 6 inclusive. In Fig. 1, and also Fig. 2, it will 70 be seen that the reference characters 1 and 2 designate a pair of permanent stationary abutment teeth between which the bridge, designated generally by the reference character 3, is adapted to be mounted. The 75 bridge comprises a dummy tooth 5, and a retaining crown 7 and inlay 19. These parts are of somewhat conventional form. As represented in Fig. 1, it will be seen that the abutment teeth are somewhat out of alignment, making it unusually difficult for ordinary bridgework construction to seat the bridge on these teeth. 80

In accordance with my idea, as before stated, I employ an improved coupling between the abutment tooth 2 for instance, and the complementary dummy 5. As shown in the figures now under consideration, the coupling comprises a section or part 8 and a complementary section 9. The part 8 is somewhat in the form of a metal boxing and this 85 includes right angular branches 11 and 12 respectively. The branch 11 is preferably rectangular or any desired shape in cross section, while the branch 12 is cylindrical 90 or any shape. These branches are braced somewhat by a reinforcing web 13 used to make it easier for solder or casting metal to flow around it in the construction of a bridge. On the open end of the branch 12 95 is a square, or any desired shape, outstanding flange 14. The part 9 comprises a cup 15 forming a keeper seat and an outstanding rectangular, or any shaped, flange 16 to bear against the complementary flange 14. In addition, the improved retaining device or coupling includes a cylindrical or any shaped (square, rectangular) pin 17 and a rectangular or any shaped key 18. In practice, the parts 9 which include the keeper cups 15 is 100 embedded in the inlay (or any other kind of abutment that is desired) 19 in the abutment

105

110

115

tooth 2 with the open side of the cup disposed toward the left as shown in Fig. 1. The complementary part 8 is embedded in the dummy at the time the latter is formulated.

5 In this connection, it is to be stated that it is necessary to plug the open ends of the branches 11 and 12 during the construction (casting or soldering) process in order to prevent them from becoming clogged. Any 10 suitable filler (preferably graphite points) may be employed for this purpose. Obviously, when the two parts are thus anchored to the respective parts of the bridge, the bridge can be readily seated by placing the 15 crown 7 on the abutment tooth 1 and bringing the two flanges 14 and 16 into meeting contact as shown in the drawings.

At this time, the cylindrical coupling pin 17 is in place, but the inlay 18 is removed. 20 This allows the pin 17 to be pushed back into the branch 11 so that it will not project and interfere with the assembling of the bridge. However, in order to project this coupling 17 in order to effect a lock, it is 25 pushed outwardly by suitable instrument, and then the key 18 is cemented into position to hold the pin in place.

During the process of assembling the bridge, the flanges 14 and 16 prevent solder 30 or casting gold to flow in the socket and help it to flow to the desired area. In Figs. 7 and 8, the reference characters 20 and 21 represent the abutment teeth and 22 and 23 the dummies. In this form, a coupling is 35 substantially the same, one part being indicated by the reference character 24 and the complementary parts by the reference character 25. The part 24 includes a rectangular or any other shaped branch 26 and a 40 right angularly extending cylindrical or any other shaped flange 27 both of which are connected together by reinforcing webs 28. On the other hand, the part 25 is simply in the form of a cup. In fact, the only difference between the two embodiments is the omission of the flanges 14 and 16 in the embodiment represented in Figs. 9 and 10. The products can be manufactured with or 45 without the flanges or both ways. The 50 flanges are of no great advantage in casting around them but are advantageous in soldering. The method of installation of the last-named embodiment is the same as that previously explained.

55 From the foregoing description, it will be seen that I have evolved and produced a novel coupling to facilitate assembling of bridge work, where the abutment teeth are not at proper angles to each other to facilitate installation of the bridge. The construction of the improvement is such that it permits the production of a removable joint between the two abutment teeth so that they 60 may move independently of each other in functioning. The invention is inexpensive

and practical, and operates efficiently, and is equally efficient to handle by a dentist. It is highly desirable in the construction of a two piece bridge.

A further advantage, is in being able to 70 lock the pieces of the bridge together permanently after they have been attached. A still further advantage is in casting or soldering the bridge, as the case may be, on the attachment while the parts of the attachment 75 that are to be cast or soldered to are in their respective relation to the parts of the bridge without undue trouble.

It is believed that the construction, and methods of installation and advantages of 80 the invention will become apparent after reading the description in connection with the drawings. For this reason, a more lengthy description is thought unnecessary.

85 Minor changes coming within the field of invention claimed may be resorted to if desired.

Having thus described my invention, what I claim as new is:—

1. As a new article of manufacture, means 90 for effecting a connection between a bridge tooth and an adjacent complementary abutment tooth, said means comprising a keeper adapted to be carried by one of said teeth, a connecting pin adapted to have one end seated in said keeper, a complementary part adapted to be carried by the remaining tooth, said part including a socket for slidable reception of said pin, socket being of a length to allow 95 the pin to be slid entirely within the socket in order to disconnect the pin from the keeper, and retaining means slidably mounted in said complementary part and separate and independent from said pin and adapted to abut one end of the latter.

100 2. As a new article of manufacture, means affording a connection between a bridge tooth and an abutment tooth, a special coupling comprising a keeper adapted to be mounted upon one of the teeth, a complementary part including a socket, a pin slidable in said socket and adapted to be received, at one end in said keeper, and a removable key associated with said part and with said 105 pin for maintaining the pin in place.

110 3. As a new article of manufacture, a bridge coupling of the class described comprising a cup adapted to serve as a keeper, a complementary part including right angular branches, a connecting pin slidable in one of the branches and adapted to have one end projected into said keeper, and a retaining key for reception in the other branch and adapted to hold said pin in place.

120 4. As a new article of manufacture, a bridge coupling of the class described comprising a cup adapted to serve as a keeper, a complementary part including right angular branches, a connecting pin slidable in one of the branches and adapted to have one end 125

projecting into said keeper, a retaining key for reception in the other branch and adapted to hold said pin in place, one of said branches being cylindrical in cross section, 5 said pin also being cylindrical, the remaining branch being rectangular in cross section and said key being rectangular in cross section.

5. As a new article of manufacture, a 10 tooth bridge coupling comprising a cup pro-

vided with an outstanding flange at its open end, a complementary part embodying right angularly disposed hollow branches, a connecting and reinforcing ridge between said branches, an outstanding flange carried by 15 the open end of one of the branches, a coupling pin, and a retaining key.

In testimony whereof I affix my signature.

GEORGE A. YANTIS.
